(57) **CLAIM**

The ornamental design for a gate upright, as shown and described.

DESCRIPTION

FIG. 1 is a perspective view of a gate upright showing my new design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The gate upright is shown with a symbolic break in its length. The appearance of any portion of the article between the break lines forms no part of the claimed design.
